UNITED STATES PATENT OFFICE.

THOMAS WINTER NICHOLS, OF GATESHEAD, ENGLAND.

VALVE-ACTUATING MECHANISM FOR FLUID-PRESSURE MOTORS.

1,203,645.

Specification of Letters Patent. Patented Nov. 7, 1916.

Application filed September 3, 1915. Serial No. 48,782.

To all whom it may concern:

Be it known that I, THOMAS WINTER NICHOLS, a subject of the King of England, residing at Gateshead, county of Durham, in England, have invented certain new and useful Improvements in Valve-Actuating Mechanism for Fluid-Pressure Motors, of which the following is a specification.

This invention relates to improvements in valve actuating mechanism for fluid pressure motors. The motor is of the type used for direct acting pumps and the like, in which no crank shaft is employed.

The object is to give a motion to the valve-rod, similar to that given by an eccentric, by mechanism actuated by the piston-rod of the motor, and the invention, broadly stated, comprises a rocking member connected to the valve-rod or equivalent and to a member adapted to be reciprocated on a stationary element, the said rocking member being actuated by a lever or levers fulcrumed on and capable of sliding movement relatively to said stationary element or to the piston-rod, whereby the latter in its movements first causes a movement of the rocking member away from the piston-rod followed by a sliding movement of the reciprocating member on the stationary element, which results in the rocking member being brought to a position in its original plane but remote from its first position and thus actuating the valve.

Embodiments of the invention are illustrated in the accompanying drawings, in which—

Figure 1 is an elevation of one form of the improved mechanism with the piston-rod of the motor at the extreme upper limit of its stroke. Fig. 2 is a plan view of Fig. 1, and Fig. 3 is a similar view to Fig. 1 when the piston is at its lower limit of stroke. Fig. 4 is an elevation showing a modification. Fig. 5 is a sectional elevation showing a further modification. Fig. 6 is a plan view of Fig. 5, and Fig. 7 a detail view in section on line A—A of Fig. 5.

In the construction shown in Figs. 1 to 3, a stationary element such as a pillar 2 preferably of circular section for carrying the motor is placed in the same plane, between, and parallel to, the piston-rod 3, and the valve actuator such as the rod 4 of said motor, and nearest the valve-rod although said pillar 2 may be placed in any other convenient position. At a suitable position

the pillar is increased in diameter as shown at 5 and through this part, and at right angles to the plane of the rods, a swivel-pin 6 projects on both sides. On the pillar 2, between the latter and the piston-rod 3, is placed a reciprocable member comprising two sleeves 7 and 8 which are spaced apart, with the swivel-pin 6 between them, and are connected together by a distance bolt 9 which, if necessary, may be adjustable. On the bolt is a sliding gudgeon 10 in the form of a sleeve with projecting pins 11 at each side, on which are mounted blocks 12 free to turn on said pins. On the side of each sleeve 7, 8 opposite to the connecting bolt 9 is a double eye, and links 13, 17 of suitable length, on the outside of each eye connect said sleeves to double eyes on rings 16, 20 by pins 15 and 19 respectively. The two rings 16 and 20 are connected together by a distance-bolt 21, adjustable as to length if necessary. The distance bolt 21, rings 16, 20 and links 13, 17 constitute a rocking member. The valve-rod 4 is connected by an eye and pin connection 22 to the upper end of the distance-bolt 21, and on the latter is a sliding gudgeon 23 with a fixed pin 24 at each side. A gudgeon 25 with a swivel-pin 26 is fixed on the piston-rod 3 by means of set bolts 27 or other means and two actuating levers 28, one on each side, are fixed to said pin 26 and pass through holes in the blocks 12 of the gudgeon 10 on the sleeve bolt 9 and also through the swivel-pin 6 in the pillar 2 and have their other ends 29 shaped to fit on the pins 24 of gudgeon 23 on bolt 21.

The action of the mechanism described is as follows: The gudgeon 25 on the piston-rod 3 is at its highest position when the piston is at the top of its stroke, this position being indicated in Fig. 1. The pivot 26 is obliged to travel in a vertical line as the piston-rod moves downward, so that the actuating levers 28 are forced through the sleeve gudgeon-blocks 12 and swivel-pin 6 in the pillar, resulting in the gudgeon 23 being forced outward thus moving the links 13, 17 up toward the horizontal. The swivel-pin 6 being fixed becomes a fulcrum for the levers 28, and the sleeve-gudgeon 10 is moved downward to the lower sleeve 8. The movement of the piston-rod still continuing, both sleeves 7 and 8 are moved downward on the pillar 2. When the actuating levers 28 have reached the half range, the links 13,

17 will be approximately horizontal, and the ring-gudgeon 23, at its extreme horizontal range. As said actuating levers continue to descend, the links will be turned upward until at the bottom of the range of the levers, the links will be again vertical but reversed, as indicated in Fig. 3.

In the construction shown in Fig. 4, instead of connecting the sleeves 7 and 8 by a distance-bolt they are connected by a bracket 30 provided with adjusting screws 31 to regulate the travel of a block 32 which slides in said bracket 30, pins 33 being provided integral with block 32. In this case 15 the actuating-levers 28 are pivoted on said pins 33, and free to slide through holes in the pins 26 and 6, their ends 29 being fitted on the pins 24.

In the construction shown in Figs. 5, 6 and 20 7, the bracket 30, block 32 and adjusting screws 31 are also provided, but the block 32 has a loose through pin 34 free to slide horizontally in a slot 35 in said block. The ends of the pin 34 pass through the actuating-levers 28. The pin 6 in the pillar 2 is 25 fixed in enlargement 5 and the actuating-levers 28 are pivoted on the reduced ends of said pin 6. In some cases a locking bolt may be provided to prevent the sleeves moving 30 until the block 32 comes against either the top or bottom sleeve or its adjusting screws. A suitable arrangement is shown in Figs. 5 and 7, where 36 is a bolt working in the pin 6 and pillar enlargement 5 against a spring 35 37, the bolt having a tapered head 38 with projections 39 adapted to fit into recesses 40 in the face of bracket 30. As the block 32 passes over the tapered head of the bolt the latter is forced back until the projections 39 leave the recesses 40, whereupon the bracket 30 is free to move with respect to the pillar 2 until the opposite end of movement is attained, when it is again locked.

The remaining reference characters in 45 Figs. 4 to 7 designate corresponding parts to those described with reference to Figs. 1 to 3. The mechanism described can also be used on ordinary engines with crank shafts, the gudgeon 25 being fixed either directly or indirectly on or to the piston-rod.

50 Details of construction described above may be modified within limits prescribed by the appended claims to suit particular cases and give the same result without departing 55 from the spirit of the invention.

What I claim as my invention and desire to secure by Letters Patent of the United States is:

1. In valve actuating mechanism for fluid 60 pressure motors, the combination of a stationary element, a piston-rod and a valve actuator disposed in planes substantially parallel to said element, a rectilinearly reciprocatable member on said stationary element, a rocking member connected to the valve actuator and

70 to said reciprocatable member, and an actuating lever fulcrumed in said stationary element and in operative connection with the piston-rod, rocking member and reciprocatable member.

2. In valve actuating mechanism for fluid pressure motors, the combination of a stationary element, a piston-rod and a valve-rod disposed in planes substantially parallel 75 to said element, a member rectilinearly reciprocatable on said element, a sliding gudgeon carried by said reciprocatable member, a rocking member connected to the valve-rod and to said reciprocatable member, and an actuating lever fulcrumed on said element, in operative connection at opposite 80 ends with the piston-rod and rocking member, respectively and intermediate said ends with said sliding gudgeon.

3. In a valve actuating mechanism for 85 fluid pressure motors, the combination of a stationary element, a piston-rod and a valve actuator disposed in planes substantially parallel to said element, a rectilinearly reciprocatable member mounted on said stationary element, a rocking member connected to the valve actuator and to said reciprocatable member, a sliding gudgeon carried by the latter, and a valve actuating lever 90 fulcrumed on said stationary element and 95 in operative connection with said piston-rod, rocking member and gudgeon, said lever being also in sliding relation with said sliding gudgeon.

4. In valve actuating mechanism for fluid 100 pressure motors, the combination of a stationary element, a piston rod and valve actuator disposed in planes substantially parallel to said element, a rectilinearly reciprocatable member mounted on said stationary element, a rocking member including 105 interconnected links pivoted to said reciprocatable member and to the valve actuator, and a valve actuating lever, pivotally connected to said rocking member, fulcrumed 110 on the stationary element and operatively connected to the piston-rod and reciprocatable member.

5. In valve actuating mechanism for fluid 115 pressure motors, the combination of a stationary element, a piston-rod and a valve actuator disposed in planes substantially parallel to said element, a rectilinearly reciprocatable member mounted on said stationary element, a rocking member connected 120 to the valve actuator and to said reciprocatable member, a sliding gudgeon carried by the latter, a valve actuating lever fulcrumed on said stationary element and in operative connection with said piston-rod, 125 rocking member and gudgeon and means for preventing movement of said reciprocating member until its gudgeon reaches its extreme limits of movement.

6. In valve actuating mechanism for fluid 130

pressure motors, the combination of a stationary element capable of supporting the motor, a piston-rod and a valve actuator disposed in planes substantially parallel to said element, a rectilinearly reciprocatable member mounted on said stationary element, a sliding gudgeon carried by the latter, a rocking member connected to the valve actuator and to said reciprocatable member and 10 a valve actuating lever fulcrumed on said stationary element and in operative connection with the piston rod, reciprocatable member and rocking member whereby the movement of the piston-rod causes firstly a move-

ment of the rocking member away from the 15 piston-rod, followed by a sliding movement of the gudgeon and a similar movement of the reciprocatable member resulting in said rocking member assuming a position in its original plane but remote from its initial 20 position.

In witness whereof I have signed this specification in the presence of two witnesses.

THOMAS WINTER NICHOLS.
